UNITED STATES PATENT OFFICE.

DONALD S. BARROWS, OF ROCHESTER, NEW YORK, ASSIGNOR TO THE T. H. SYMINGTON COMPANY, OF NEW YORK, N. Y., A CORPORATION OF DELAWARE.

CAR UNDERFRAME.

Application filed June 20, 1922. Serial No. 569,706.

To all whom it may concern:

Be it known that I, DONALD S. BARROWS, a citizen of the United States, residing at Rochester, in the county of Monroe and State of New York, have invented certain new and useful Improvements in Car Underframes; and I do hereby declare the following to be a full, clear, and exact description of the invention, such as will enable others skilled in the art to which it appertains to make and use the same.

My invention relates to car underframes for railway cars and more particularly to a strong, reliable and efficient metallic structure adapted to be applied generally to wooden underframe cars to reinforce the underframes thereof so as to adapt said cars for use under modern service conditions.

To this end the principal object of my invention, generally stated, is to provide a metallic structure adapted to be used with the underframe of wooden cars, said structure being used to reinforce the car sills so that buffing and pulling shocks which exceed the capacity of the draft rigging are transmitted to the underframe at a plurality of spaced points in the most advantageous manner.

Another object of my invention, generally stated, resides in the combination of a car underframe and spaced metallic center sill reinforcing members adapted to be connected to the center sills of the car, spaced draft sills arranged beneath the center sills, a backstop member connected to the inner ends of the draft sills, said backstop member being spaced from the bolster of the car and adapted to bridge the inner ends of the draft sills, and means involving a gusset plate for firmly uniting the center sill reinforcing members with the draft sills.

Another object of my invention is to provide a car underframe including in combination center sill reinforcing means connected to the center sills of a railway car, draft sills arranged beneath the center sills, said draft sills terminating short of the bolster and having formed at their inner ends a backstop member, and an interposed connecting means riveted to the center sill reinforcing means and draft sills, said connecting means being adapted to firmly unite the center sill reinforcing means and draft sills with the bolster at a plurality of points.

A further object of the invention is to

provide a metallic structure which can be easily applied to underframes of cars at a comparatively small cost with minimum expenditure of labor, thereby permitting employment of modern types of draft rigging in combination with underframes of cars requiring modifications or changes to bring them within the present M. C. B. standards.

A still further object of my invention, generally considered, is to provide means in connection with a draft rigging having a slidable connection between the coupler and yoke member, said means including wrought members connected to the car sills and positioned in rear of said yoke member to hold the same from rearward movement to transmit buffing shocks to said sills.

There are other features of the invention as will be pointed out hereinafter in connection with the detailed description of the embodiments of my invention illustrated in the accompanying drawings in which—

Figure 1 is a plan view of my improved metallic construction, a portion thereof being broken away to more clearly illustrate the associated parts, and a portion of the rear end of the movable element of the draft rigging being shown.

Figure 2 is a vertical longitudinal sectional view on the line 2—2 of Figure 1. 85

Figure 3 is a horizontal sectional view on the line 3—3 of Figure 2.

Figure 4 is a vertical transverse sectional view on the line 4—4 of Figure 2.

Figure 5 is a detail view of the rear end of the draft sills illustrating a modified form of channel loop construction connecting the inner ends of the draft sills and associated backstop.

Figure 6 is a vertical transverse sectional view on the line 6—6 of Figure 5.

Figure 7 is a view partly in plan and partly in section illustrating still another form of my invention wherein an integral end or yoke portion connects the inner ends of the draft sills.

Figure 8 is a vertical longitudinal sectional view through the form of car underframe and backstop member shown in Figure 7.

Figure 9 is a detail vertical transverse sectional view on the line 9—9 of Figure 8. 105

In the drawings I have illustrated only a portion of the car underframe adjacent the body bolster. It is to be understood, how-

ever, that the structure is duplicated at the opposite end of the car and that the center sills hereinafter referred to may be extended a distance of several feet beyond the bolster 5 toward the center of the car. The car underframe preferably includes the usual end sill and associated parts, not shown, but as is well understood by those skilled in the art.

Referring to the drawings in which corresponding reference characters designate similar parts in the several views, the center sills of the car are provided with center sill reinforcing means, said reinforcing means including spaced angle members or sills 15 1-1 adapted to be connected to the said center sills of the car underframe. The bolster may be of the usual construction, the arm portions 2-2 thereof extending transversely of the car upon either side of the center sills, and being interconnected with the bolster center filler 3, the latter being provided with the center thimble 4.

The draft sills 5-5 are connected to the bottom flanges of the center sill reinforcing means by means of rivets 7. A tie member or cover plate 8 of channel construction bridges and unites the upper web portions of the center sill reinforcing members, thereby further bracing said reinforcing members. The inner ends of the draft sills terminate short of the bolster and provided at said inner ends is a backstop member 9, said backstop member being preferably spaced from the bolster and adapted to receive buffing shocks from a movable element of the draft rigging, shown herein as the yoke 10, of the well known Farlow equipment.

The backstop member 9 is formed of an end wall portion 11 arranged in the shape of a loop or strap which, together with the forwardly extending portions 12 thereof, produces a horizontal U-shaped yoke member bridging and connecting the inner ends 45 of the draft sills. Each forwardly projecting portion 12 is connected at a plurality of points by means of rivets 13 to the respective web portions of each draft sill, said rivets being arranged so as to provide 50 a strong and rigid connection between draft sills and the curved end wall of the backstop member. The backstop casting 14 is connected to the curved end wall portion 11 by means of rivets 15, said casting being suitably reinforced by a plurality of webs or flanges 16 joining opposite end walls of the casting. The rear wall of the backstop casting 14 is curved and is designed to fit the interior face of the end wall portion 60 of the U-shaped member. The front wall of said backstop casting is formed with a buffing face adapted to receive the buffing shocks incident to service through the yoke member 10. The front wall is designed to 65 rearwardly merge into the curved or rear

wall of the casting in the angular manner as shown in Figure 1.

The top flange of each draft sill is extended rearwardly beyond the buffing face of the backstop member, as shown at 17, the rivets 7 uniting the center sill reinforcing members or bars, and draft sills preferably extending the length of said top flanges, thereby providing a strong and durable connection capable of transmitting buffing 75 shocks to the forward portions of the center sills and throughout the length of the reinforcing means connected to said center sills.

The means interposed between and connecting center sill reinforcing members, draft sills and bolster, include a gusset plate 18 connected to the projecting arms 2 of the bolster by means of rivets 19. Opposite forwardly projecting portions 20 are provided adjacent a central cut-away portion of the gusset plate, said projecting portions extending forwardly of the backstop member and being connected by means of a relatively large number of the connecting rivets 7 80 to the bottom flanges of the center sill reinforcing members and the upper flanges of the draft sills, including the rearwardly extending upper portion 17 of said upper draft sill flanges. The gusset plate covers 85 a relatively large area, the rearwardly extending portions of the upper flanges of the draft sills providing an additional riveting area in the rear of the backstop and serving to interconnect the center sill reinforcing means, the associated draft sills and backstop, so that buffing strains will be transmitted from the draft sills to the forward ends of the center sills as well as through the gusset plate to the bolster. 95

Filler strips 21 may be interposed between the upper flanges of the draft sills and the bottom flanges of the reinforcing members, said strips being provided forwardly of the gusset plate projecting portions 20, as shown. Other filler strips or shims 22 may be interposed between the gusset plate and the top flanges of the draft sills, and it will be understood that the proper level of the parts can be determined 115 by the interpositioning of said filler strips.

In the construction shown in Figures 5 and 6, the strap or loop member 23 connecting the inner ends of the draft sills is of channel shape, the forwardly projecting portions 24 of which are firmly connected to the inner ends of the draft sills by means of rivets 25. A backstop casting 26 is connected to the vertical wall or web portion of the channel upon the interior face thereof, said casting having a curved rear wall contacting the interior curved face of the channel bar and being provided with a front wall forming the buffing face against which the yoke member of the draft rigging abuts 120 125 130

upon buffing movement. Reinforcing and bracing webs 27 are formed on the backstop member, as shown. Rivets 28 connect said casting 26 to the looped channel bar. It 5 will be apparent that the arrangement of the looped channel bars uniting the inner ends of the channel draft sills provides a strong and durable construction, the result of said construction constituting a channel 10 within a channel, as clearly shown in Figure 6. The means uniting the draft sills and center sill reinforcing means is the same as shown in Figure 1 and a description thereof in connection with the present form is believed to be unnecessary.

The form of construction shown in Figures 7, 8 and 9 includes a yoke or U-shaped member 29 preferably of channel shape in cross section, the relatively long parallel 20 arms of said yoke member constituting a draft sill and the integral end portion forming a curved rear wall to which is connected the backstop casting 31. The backstop casting is provided with a front wall and buffing face 25 cooperatively associated with the movable yoke member. A curved rear wall is formed on the backstop casting, rivets 32 passing through said wall and serving to firmly connect the casting to the interior face of the 30 curved rear wall of the U-shaped or yoke member 29. Vertical and horizontal bracing webs or flanges 33 are formed on the backstop casting for reinforcing the buffing wall, as will be understood.

35 The means connecting the upper flanges of the contiguously formed draft sills to the center sill reinforcing members includes a gusset plate 34 interposed between the reinforcing sills and the upper flanges or the 40 draft sills, said gusset plate bridging the respective sills and having portions thereof connected to the bolster of the car underframe, as clearly shown in Figure 7. The gusset plate is provided with projecting portions 35, said portions extending forwardly 45 of the draft sills and backstop member. Rivets 36 firmly unite the several parts together, said rivets passing through the gusset plate and adjacent upper flanges of the draft 50 sills and bottom flanges of the center sill reinforcing members. In this form of the invention it will be seen that the rivet connecting means extends continuously around the rear end portion of the draft sills, there- 55 by providing an increased and particularly effective riveting area for uniting the several parts, which, together with the integral form of bent draft sills, provides a comparatively simple, strong and durable construction in 60 which buffing shocks can be taken through the backstop member and transmitted to the forward portions of the center sills as well as to the bolster and connecting gusset plate.

65 An underframing for railway cars con-

structed in accordance with my present invention, as referred to in the several embodiments above described, permits the buffing loads being effectively transmitted to the car center sills at points where the latter are best able to withstand the excessive strains. In addition, it will be obvious that an underframe is conveniently and inexpensively provided for older types of cars wherein modern draft rigging equipment can be 70 easily installed.

I claim:

1. In a car underframe, the combination with center sills and bolster, of center sill reinforcing means connected to said center sills, draft sills arranged beneath the center sills and reinforcing means, means connecting said center sill reinforcing means and draft sills and a backstop member provided at the inner ends of said draft sills and spaced from said bolster.

2. In a car underframe, the combination with center sills and bolster, of center sill reinforcing means connected to said center sills, draft sills arranged beneath the center sills and reinforcing means, rivet means adapted to firmly unite the center sill reinforcing means and draft sills at a plurality of points, and a backstop member provided at the inner ends of the draft sills, said 95 backstop member being spaced from the bolster and arranged within the longitudinal area of said rivet connecting means.

3. In a car underframe, the combination with center sills and bolster, of center sill reinforcing means connected to said center sills, draft sills arranged beneath the center sills and reinforcing means, a backstop member connected to the inner end of said draft sills and spaced from said bolster, means 100 interposed between said draft sills and center sill reinforcing means and adapted to bridge the same, and means passing through said interposed means, draft sills and center sill reinforcing means for firmly connecting 105 said parts together.

4. In a car underframe, the combination with center sills and bolster, of center sill reinforcing means connected to said center sills, draft sills arranged beneath the center sills and reinforcing means, a backstop member connected to the inner ends of said draft sills and spaced from said bolster, means including a gusset plate arranged 115 between a center sill reinforcing means and draft sills, and rivet means adapted to firmly unite said gusset plate, draft sills and center sill reinforcing means.

5. In a car underframe, the combination with center sills and bolster, of center sill reinforcing means connected to said center sills, draft sills arranged beneath the center sills and reinforcing means, a backstop member connected to the inner ends of said draft sills and spaced from said bolster,

means including a gusset plate having portions projecting forwardly of the backstop member, said gusset plate and projecting portions being interposed between the center 5 sill reinforcing means and draft sills, and means for firmly connecting said gusset plate, draft sills and center sill reinforcing means, a portion of said connecting means passing through the forwardly projecting 10 portions of the gusset plate.

6. In a car underframe, the combination with center sills and bolster, of center sill reinforcing means connected to said center sills, draft sills arranged beneath the center 15 sills and reinforcing means, a backstop member connected to the inner ends of said draft sills, means including a gusset plate having portions projecting forwardly of the backstop and connected to the center sill reinforcing means and draft sills, said gusset plate being arranged to bridge the draft sills and having portions thereof connected to the bolster of the car underframe.

7. In a car underframe, the combination with center sills and bolster, of center sill reinforcing means connected to said center sills, draft sills arranged beneath the center sills and reinforcing means, a backstop member connected to the inner ends of said draft 20 sills and spaced from said bolster, and means bridging and connecting said draft sills and bolster, said means having portions thereof connected to the center sill reinforcing means forwardly of the backstop member.

35 8. In a car underframe, the combination with spaced center sills, reinforcing center sill members connected to said center sills, means bridging and connecting said reinforcing members, draft sills arranged beneath the center sills and connected to said center sill reinforcing members, and a backstop member bridging the space between said draft sills and connected to the faces thereof.

45 9. In a car underframe, the combination with spaced center sills, reinforcing center sill members connected to said center sills, means bridging and connecting said reinforcing member, draft sills arranged beneath the center sills and connected to said center sill reinforcing members, means interposed between said draft sills and center sill reinforcing member, said means bridging the draft sills and being connected 50 thereto and the center sill reinforcing members at a plurality of points longitudinally of the car underframe, and a backstop member provided at the inner ends of said draft sills within the longitudinal area of the draft sills and center sill reinforcing members.

60 10. In a car underframe, the combination with spaced center sills, reinforcing center sill members connected to said center sills, means bridging and connecting said rein-

forcing members, draft sills arranged beneath the center sills and connected to said center sill reinforcing members, means forming an end closure wall at the rear of said draft sills, a backstop member connected to 70 said wall and means connecting the draft sills and center sill reinforcing means, said connecting means extending forwardly of the backstop member.

11. In a car underframe, the combination 75 with spaced center sills, reinforcing center sill members connected to said center sills, means bridging and connecting said reinforcing members, draft sills arranged beneath the center sills and connected to said center sill reinforcing members, means forming a curved end wall at the inner ends of said draft sills, a backstop casting having a curved portion fitting said curved end wall, means connecting said backstop casting to said wall, and means connecting the draft sills and center sill reinforcing members, said last named connecting means extending forwardly of the backstop casting.

12. In a car underframe, the combination 80 with center sills, of center sill reinforcing means, draft sills arranged beneath the center sills and connected to said center sill reinforcing means, means bridging and connecting said center sill reinforcing means 85 and draft sills, a yoke member connecting the inner ends of said draft sills, and a backstop member connected to said yoke member.

13. In a car underframe, the combination 90 with center sills and bolster, of center sill reinforcing means connected to said center sills, draft sills arranged beneath and connected to said center sill reinforcing means, means bridging and connecting said bolster, center sill reinforcing means and 100 draft sills, a yoke member spaced from said bolster and connecting the inner ends of said draft sills, and a backstop portion provided on said yoke member cooperatively associated with a movable element of a draft 105 rigging.

14. In a car underframe, the combination 110 with center sills, of center sill reinforcing means connected to said center sills, draft sills arranged beneath and connected to said center sill reinforcing means, means bridging and connecting said bolster, center sill reinforcing means and draft sills, and a relatively fixed yoke member connecting the inner ends of said draft sills and adapted 115 to form a rear abutment for the movable yoke member of a draft rigging.

15. In a car underframe, the combination 120 of sill members with a backstop member, said backstop member including a strap connecting said sill members forwardly of the rear end of the movable element of a draft rigging.

16. In a car underframe, the combination 125 of sill members with a backstop member,

said backstop member including a loop member having arms projecting forwardly of said sill members and connected thereto.

17. In a car underframe, the combination of sill members with a backstop member, said backstop member including a wrought member connecting said sill members forwardly of the rear end of the movable element of a draft rigging.

18. In a draft rigging, the combination with a yoke member, of a coupler slidably connected thereto, sill members between which said yoke member is positioned, and means including a strap connected to said sill members forwardly of the adjacent end of said yoke member for transmitting buffing strains to said sill members.

19. In a draft rigging, the combination with a yoke member, of a coupler slidably connected thereto, and sill members between which said yoke member is positioned, said sill members forming a backstop portion continuous therewith for transmitting buffing strains to said sill members.

20. In a draft rigging, the combination with a yoke member, of a coupler slidably connected thereto, sill members between which said yoke member is positioned, and means including a curved strap connected to said sill members forwardly of the adjacent end of said yoke for transmitting buffing strains to said sill members.

21. In a draft rigging, the combination

with a yoke member, of a coupler slidably connected thereto, sill members between which said yoke member is positioned, means including a strap connected to said sill members forwardly of the adjacent end of said yoke member, a casting having a buffering face adapted to receive and transmit buffering strains through said strap to the sill members, and means connecting said casting to said strap.

22. The combination with car sills, of a wrought strap connected thereto, and means on said strap for engaging a movable element of the draft rigging.

23. A draft rigging backstop involving a wrought loop member having forwardly projecting arms adapted to be connected to the draft sills of a railway car.

24. A draft rigging backstop involving a loop member formed with forwardly projecting arms and adapted to be connected to the draft sills of a railway car, and a casting having a buffering face, said casting being connected to said loop member.

25. A draft rigging backstop formed by the continuation of draft sill members transversely of the car underframe for permitting buffering strains to be transmitted to said sill members forwardly of the rear end of a movable element of the draft rigging.

In testimony whereof I affix my signature.

DONALD S. BARROWS.
